J. RIDDLE

SIPHON AND LIKE RECORDER

Filed Nov. 21, 1924

Fig. 1.

Fig. 2.

INVENTOR:

JOHN RIDDELE,

By his Attorneys,
Macdonald Wright

UNITED STATES PATENT OFFICE.

JOHN RIDDLE, OF LONDON, ENGLAND, ASSIGNOR TO TELEGRAPH CONSTRUCTION
AND MAINTENANCE COMPANY, LIMITED, OF LONDON, ENGLAND.

SIPHON AND LIKE RECORDER.

Application filed November 21, 1924, Serial No. 751,290, and in Great Britain August 16, 1924.

This invention relates to recording instruments of the type in which a movement of a siphon, pen or other marking instrument is recorded on a moving slip of paper or the like.

5 The invention is particularly applicable to receiving instruments of delicate construction, such as are employed for recording the weak current reversals transmitted through submarine cables of great length.

10 The invention relates more particularly to improved means for vibrating the siphon or other marking instrument towards or away from the paper, to minimize friction and ensure a ready flow of ink.

15 According to the present invention, a strip of flexible material, such as phosphor bronze or silk carrying the siphon, pen or other marking instrument, is vibrated laterally (viz. in a direction at right angles to its axis) by means of a buzzer or the like acting to pull upon one end of the said strip, the other end of the strip being either fixed, or preferably connected to a spring, by 20 means of which the strip can be put under the desired amount of tension.

25 In the accompanying drawing which shows diagrammatically one way of carrying out my invention, as applied to a siphon recorder applicable for use with a submarine cable, Figure 1 is a plan and Figure 2 is an elevation of Figure 1, some of the parts being omitted from the figures for the sake of clearness.

30 35 1, 1 are the poles of a permanent magnet and 2 is a coil to which the cable is connected and which is delicately suspended in the usual manner in the field of the magnet. 3 is a strip of phosphor bronze to which is 40 fastened a carrier 4 for a siphon pen 5, one end of which dips into an ink reservoir 6, while the other marks a travelling strip of paper 7, passing over rollers 8 in the usual manner.

45 45 The strip 3 is connected at one end to the armature 9 of a buzzer 10 of usual construction, while the other end is connected to a spring 11 by means of which the strip is put under tension.

50 50 The coil 2 is connected to the carrier 4 by a glass tube 12 having at its ends short strips of phosphor bronze 13, 14, which are sufficiently flexible to allow the necessary turning movement of the coil and the carrier. The end of the strip 13 is provided

55 with an eye which engages a pin 15 on the coil 2, while the end of the strip 14 is provided with a hook to enable it to engage any desired one of a number of holes 16 in the carrier 4.

60 In operation the armature 9 of the buzzer 10 acting to pull on the end of the strip 3 causes the strip to vibrate laterally, viz. in a direction at right angles to its axis.

65 What I claim is:—

1. In a recording instrument of the type in which a movement of a marking instrument is recorded on a moving slip of material, the combination of a strip of flexible material, a marking instrument carried wholly by said strip, and means giving a rapid intermittent pull upon one end of said strip longitudinally thereof to vibrate said strip laterally or at an angle to the direction of its length toward and away from the slip of material. 75

2. In a recording instrument of the type in which a movement of a marking instrument is recorded on a moving slip of material, the combination of a strip of flexible material, a marking instrument carried wholly by said strip, and a buzzer giving a rapid intermittent pull upon one end of said strip longitudinally thereof to vibrate said strip laterally or at an angle to the direction of its length toward and away from the slip of material. 85

3. In a recording instrument of the type in which a movement of a marking instrument is recorded on a moving slip of material, the combination of a strip of flexible material, a marking instrument carried by said strip, a spring to which one end of the strip is connected, and means giving a rapid intermittent pull upon one end of said strip longitudinally thereof to vibrate said strip laterally or at an angle to the direction of its length toward and away from the slip of material. 95

4. In a recording instrument of the type in which a movement of a marking instrument is recorded on a moving slip of material, the combination of a strip of flexible material, a marking instrument carried by said strip, a spring to which one end of the strip is connected, and a buzzer giving a rapid intermittent pull upon one end of said strip longitudinally thereof to vibrate said strip laterally or at an angle to the direction of its length toward and away from the slip of material. 105 110

5. In a recording instrument of the type in which a movement of a marking instrument is recorded on a moving slip of material, the combination of a strip of flexible 5 springy material, a marking instrument carried by said strip, and means giving a rapid intermittent pull upon one end of said strip longitudinally thereof to vibrate said strip laterally or at an angle to the direction of its length toward and away from the slip of material.
- 10 10. In a recording instrument of the type in which a movement of a marking instrument is recorded on a moving slip of material, the combination of a strip of flexible 15 springy material, a marking instrument carried by said strip, and a buzzer giving a rapid intermittent pull upon one end of said strip longitudinally thereof to vibrate said strip laterally or at an angle to the direction of its length toward and away from the slip of material.
- 15 15. In a recording instrument of the type in which a movement of a marking instrument is recorded on a moving slip of material, the combination of a strip of flexible 20 springy material, a marking instrument carried by said strip, and a buzzer giving a rapid intermittent pull upon one end of said strip longitudinally thereof to vibrate said strip laterally or at an angle to the direction of its length toward and away from the slip of material.
- 20 20. In a recording instrument of the type in which a movement of a marking instrument is recorded on a moving slip of material, the combination of a strip of flexible 25 springy material, a marking instrument carried by said strip, and a buzzer giving a rapid intermittent pull upon one end of said strip longitudinally thereof to vibrate said strip laterally or at an angle to the direction of its length toward and away from the slip of material.
- 25 25. In a recording instrument of the type in which a movement of a marking instrument is recorded on a moving slip of material, the combination of a strip of flexible 30 springy material, a marking instrument carried by said strip, a spring to which one end of the strip is connected, and means giving a rapid intermittent pull upon one end of said strip longitudinally thereof to vibrate said strip laterally or at an angle to the direction of its length toward and away from the slip of material.
- 30 30. In a recording instrument of the type 35 in which a movement of a marking instrument is recorded on a moving slip of material, the combination of a strip of flexible springy material, a marking instrument carried by said strip, a spring to which one end 40 of the strip is connected, and a buzzer giving a rapid intermittent pull upon one end of said strip longitudinally thereof to vibrate said strip laterally or at an angle to the direction of its length toward and away from the slip of material.
- 35 35. In a recording instrument of the type 40 in which a movement of a marking instrument is recorded on a moving slip of material, the combination of a strip of flexible springy material, a marking instrument carried by said strip, a spring to which one end 45 of the strip is connected, and a buzzer giving a rapid intermittent pull upon one end of said strip longitudinally thereof to vibrate said strip laterally or at an angle to the direction of its length toward and away from the slip of material.

In testimony that I claim the foregoing as my invention I have signed my name this 27th day of October, 1924.

JOHN RIDDLE.
